UNITED STATES PATENT OFFICE.

HENRY BREMNER, OF BROOMHILL, GLASGOW, SCOTLAND.

CALKING-MACHINE.

1,400,138.

Specification of Letters Patent. Patented Dec. 13, 1921.

Application filed May 11, 1920. Serial No. 380,680.

To all whom it may concern:

Be it known that I, HENRY BREMNER, a subject of the King of the United Kingdom of Great Britain and Ireland, and resident 5 of 65 Marlborough avenue, Broomhill, Glasgow, Scotland, electrical engineer, have invented a certain new and useful Improved Calking-Machine, of which the following is a specification.

10 This invention relates to a machine for calking or packing seams, joints, slots or grooves and is particularly applicable for use in calking deck seams or floor joints, more especially in ships' decks, but it will be 15 understood that the invention may be utilized for calking or packing any similar type of seam, joint, slot or groove.

Heretofore, in packing seams or joints of this nature, difficulty has been experienced 20 owing to the narrowness of the slot or groove and the considerably greater dimensions of the resilient or compressible packing employed, which is usually oakum in the case of ships' deck seams. It is the principal object of the present invention to overcome 25 this difficulty and to enable comparatively narrow seams or joints, to be readily and efficiently packed with resilient or compressible packing which may be of normally considerably greater dimensions. A further object is to enable the calking or packing to 30 be effected more rapidly and economically by dispensing with the usual hand labor.

According to the present invention, an 35 enlarged seam is formed by fitting an extension or guideway to the seam or space to be packed, so that it forms an outward extension or continuation thereof, the walls of which preferably taper toward the seam and 40 are flush therewith.

The packing is supplied to this enlarged seam and rammed into its narrow extremity by a reciprocatory calking tool or hammer.

The packing may be supplied to the seam 45 extension in an uncompressed state and will be gradually compressed as it traverses through the enlarged seam, this compression being effected between the tapered walls of the seam extension under the pressure of the 50 calking tool and the drag of the packing through the seam extension, the compression gradually increasing as the packing traverses into place and the packing reaching the space to be packed in a partially compressed 55 state in which it can be effectively and solidly rammed into place by the point of the tool.

The calking machine comprises essentially a vertically reciprocated calking tool, means for feeding the oakum or like packing to the calking tool and means for guiding and traversing the calking tool along the deck.

In order that the invention may be more clearly understood reference is hereinafter made to the accompanying drawings, showing one construction of the machine by way 65 of example.

Figures 1, 2 and 3 are end, side and plan views respectively of the complete machine.

Fig. 4 is an end view and Fig. 5 a plan view of the carriage or crawling gear. 70

Fig. 6 is a detail side view of the calking tool and adjacent mechanism. Fig. 7 is an edge view of the calking tool. Fig. 8 is an inverted plan view, and Fig. 9 an end view of the parts seen in Fig. 6. Fig. 10 is a detail view of the guide block for the calking tool. 75

The seams or joints 1 of the deck or floor boards 2 to be packed are shown in Fig. 2. Fitted over the seam 1 is a funnel or tapered hollow extension (best seen in Fig. 9) which preferably comprises a pair of parallel members 3 spaced apart so as to provide a tapered opening 4 between them, the opening 4 tapering downwardly toward the 80 seam 1 and its lower extremity being of the same width as the outer edge of the seam 1, so that the opening 4 forms an outward enlarged seam extension or continuation of the 85 seam. 90

The packing is supplied to the seam extension 4 (as hereinafter described) and is rammed into the seam 1 by means of a reciprocatory calking tool or hammer 5, which is preferably wedge-shaped (as seen in Fig. 95 7) to correspond to the taper of the seam extension 4. The edge 5^a of the tool 5 may be plain, or serrated so as to exert a pull upon the packing. The tool 5 is preferably tapered downwardly in both directions, forming inclined edges 5^a, so that the point of the tool extends into the joint 1 when the tool descends, the front edge 5^a bearing against the packing. 100

The packing may be supplied to the seam extension 4 in an uncompressed state and will be gradually compressed between the tapered walls of the seam extension 4 under the pressure of the calking tool 5, the packing being continuously compressed as it is 110 moved through the seam extension 4, reaching the seam 1 in a state in which it can be

effectively and solidly rammed into place by the point of the tool 5.

As shown in Figs. 6, 8 and 9, the parallel members 3 of the seam extension may be spaced apart by central blocks 6 and intermediate plates 7, the latter forming the sides of the seam extension 4 and the blocks 6 having a curved inner profile 6^a forming a guide or runway for the packing which is supplied to the seam extension 4. The blocks 6 and plates 7 preferably extend below the parallel members 3 as seen in Fig. 6 so as to rest on the deck and lift the outer parts clear thereof.

15 The calking tool 5 and the seam extension are adapted to be traversed along the seam 1 so that the packing is fed automatically to the seam by the downward and forward pressure of the calking tool 5 against the packing and by the retention of the latter by compression in the joint.

Similar seam extensions are preferably fitted both in front of and in rear of the tool 5 (as seen in Fig. 6) so that the machine 25 may be traversed in either direction. The seam extensions may be bolted together by bolts 8 and resiliently supported by vertically movable supports 9 from the gear casing 10. If, desired, the seam extensions 30 may be guided at one or both ends by a roller or rollers or their equivalent, adapted to run in the seam 1 and thus maintain the seam extension in alinement with the joint 1. It will be readily understood that the supports 35 9 may be adjusted vertically with respect to the gear casing 10 and may be fitted with springs 11 so as to provide both positive and automatic vertical adjustment of the seam extensions.

40 The calking tool 5 is preferably power driven and of adjustable stroke, for which purpose it may be fixed within a block 12 (shown in plan in Fig. 10) said block being guided in fixed vertical guides 13 (Fig. 6) and being jointed to a link 14 pivoted to the ends of links 15 and 16, the link 15 being pivoted at its other end to the flywheel 17 which is driven by the electro motor or other prime mover 18 (Figs. 1, 2 and 3). The free end of the link 16 has a pin 19 working within a slot 20 (Fig. 1) in the gear case 10 and is connected to one end of a combined hand and foot adjusting lever 22. By adjusting the latter in any required position, the links 45 14 and 15 may be moved more or less out of alinement with each other, thus varying the lowermost position of the tool 5 and varying its stroke.

It will be seen that the mechanism just 60 described enables the tool 5 to be lifted clear of the deck or floor after each stroke, and to clear itself of threads from the packing.

Any other adjustable stroke mechanism may, however, be employed and if desired 65 the tool may be of the drop-hammer type

and controlled by springs or weights to increase the downward pressure.

The seam extensions insure that the tool properly engages the seam 1 during each down stroke, but this may be further insured, 70 if desired, by making the plates 7 project into the seam 1 and they may be spring pressed toward the tool (if required) so as to be kept in close contact therewith.

The oakum or like packing is preferably 75 mounted upon a reel or reels 23 (Figs. 1 and 2) supported in any convenient position upon a suitable carriage 24 (Figs. 4 and 5) which carries the motor, the calking tool and seam extensions. The packing 25 (Fig. 80 1) may be supplied to the seam extension 4 over a guide roller 26 and suitable guides, the roller 26 being adapted to be swung from one side of the machine to the other (as indicated in dotted lines in Fig. 1) so as to feed 85 the packing to either side of the tool 5.

The carriage 24 is fitted with crawling gear or like mechanism for traversing the machine along the deck, and said crawling gear may be reversible to enable the machine 90 to work in either direction. Figs. 4 and 5 illustrate a suitable form of carriage by way of example. The carriage 24 is supported on running wheels 27 and 28 mounted on axles 29 and 30 respectively. The axle 29 is fitted 95 with clutch mechanism 31 operated by external levers 32, the clutch mechanism 31 being interposed between the axle 29 and a chain or like drive 33 from a stub shaft 34 having a worm wheel 35 thereon which 100 gears with a worm on a worm shaft 36 driven in turn by a driving shaft 37. The shaft 37 may be driven in either direction from the motor 18 by belt or chain gearing 105 38.

To traverse the carriage across the deck or floor from seam to seam, additional running wheels 39 may be provided, eccentrically mounted upon shafts 40 adapted to be rotated by a cross-shaft 41 and operating handle 42, so as to raise or lower the wheels 39 and thus cause them to lift the machine and its running wheels 27 and 28 clear of the deck or lower the same into contact therewith. When the machine is raised, the wheels 110 39 may be rotated by wheels or pinions 43 on a shaft 44, rotated by an external crank handle 45, the pinions 43 driving one pair of wheels 39 by friction or by means of teeth thereon.

In order to insure perfect alinement during the traverse of the machine along the deck, the machine may be fitted (as shown in Figs. 1 and 3) with fore and aft alining guides or rollers 46, preferably vertically adjustable on the machine frame and running in the seam or seams in front of and in rear of the tool 5.

Claims:

1. A machine for calking or packing 130

seams, joints, slots or grooves, comprising a vertically reciprocated tool, means for feeding packing to the tool, means for guiding and traversing the tool along the seam or the like, and an extension for the reception of the tool, said extension being fitted over the seam to form an enlarged seam to which the packing is supplied and in which the tool operates.

- 10 2. A machine for calking or packing seams, joints, slots or grooves comprising a vertically reciprocated tool, means for feeding packing to the tool, means for guiding and traversing the tool along the seam or the like, and a seam extension within which the tool operates, said extension comprising parallel members forming a tapered guideway between them and a spacing block shaped to form a guide for the packing.
- 15 3. A machine according to claim 1 having seam extensions fitted both in front of and in rear of the tool.

4. A machine for calking or packing seams, joints, slots or grooves, comprising a vertically reciprocated tool, means for feeding packing to the tool, means for guiding and traversing the tool along the seam or the like, and a tapered extension for the reception of the calking tool, said extension being fitted over the seam normal thereto and open above to form an enlarged seam to which the packing is supplied and in which the tool operates.

5. A machine according to claim 4 having a wedge-shaped non-rotating tool, substantially as described.

6. A machine according to claim 4 in which the tool is lifted clear of the seam after each working stroke.

7. A machine according to claim 4 having a mechanism for traversing the machine across from seam to seam, substantially as described.

HENRY BREMNER.
